REFLUX RATIO CONTROL FOR FRACTIONATING COLUMNS

Anthony E. Robertson, New York, N. Y., assignor to Standard Oil Development Company, a corporation of Delaware

Application September 30, 1938, Serial No. 232,493

10 Claims. (Cl. 202—161)

This invention relates to a system for the operation of a fractionation column. More specifically it relates to a system for regulating the withdrawal of condensate from such a 5 column, or for controlling the reflux ratio in the column. The invention is particularly adapted for use when the distillation rate is not constant and when the process is carried out at less than atmospheric pressure.

When it is necessary to operate a fractionation column under conditions in which the distillation rate is not constant, a problem in accurate reflux control is created which requires that the withdrawal of condensate from the 10 column be so regulated as to maintain a substantially constant reflux ratio. Ordinarily, the solution is accomplished by withdrawing condensate intermittently to such extent that over a definite period of time, the desired reflux ratio is achieved. To do this it has been customary 15 to provide valves in the product recovery lines or weir boxes and the like within the column, any of which may be either manually or automatically operated. Such arrangements, however, are usually awkward and when openings 20 through the column walls are required, involve special stuffing boxes and other expedients any of which are liable to leakage. When operating under reduced pressures with such devices, it is 25 difficult to properly maintain the pressure conditions at a constant value. By means of the invention now set forth, it is possible to avoid the complicated arrangements of previous apparatus and to overcome the deficiencies inherent 30 therein.

The advantageous features of the invention as set forth above and as further disclosed herein may be fully understood from the following specification when read in conjunction with the 35 accompanying drawings, in which:

Fig. 1 shows diagrammatically, in section, one 40 arrangement of parts contemplated;

Fig. 2 shows a similar view of an alternative 45 system; and

Fig. 3 illustrates another form of the system 50 disclosed.

As shown in Fig. 1 the apparatus comprises 55 fractionating a column 1 having a condenser 2 and a packed section 3. A product recovery line 4 is disposed in the upper portion of the column 1 to receive a stream of condensate from the condenser 2. In the preferred form, the line 4 is provided with a trap 5 and an upwardly opening funnel-shaped inlet portion 6. In order to interrupt the withdrawal of condensate and

to provide for reflux in the column 1, a movable baffle means is disposed above the inlet portion 6 of the line 4. As shown, the means comprises a spring member 7, secured to one wall of the column, as at 8, and having a baffle or shelf portion 9 at its upper end extending toward the inlet 6, and providing a baffle for said inlet. The baffle 9 preferably provides an inclined surface to lead condensate away from the inlet, returning the condensate as reflux to the column. 10

The spring member 7 also carries an armature 10 which is adapted to respond to energy changes in the electromagnet 11 disposed, in this instance, outside the column. Activation of the electromagnet 11 attracts the armature 10 with 15 a force sufficient to bend the spring member 7 and cause the baffle 9 to be withdrawn from above the inlet 6 to the line 4. Obviously the arrangement of parts as disclosed may be readily altered to provide for an inlet 6 which 20 is normally uncovered and in which activation of the electromagnet operates to move the baffle over the inlet as required. In either case, the baffle 9 is returned to its normal position by the action of spring 7. Timing mechanisms, or 25 other automatic control means, not shown, may be employed to interrupt or induce activation of the electromagnet.

In Fig. 2, there is illustrated an alternate construction, which is particularly adapted for use 30 when the tower is constructed of a magnetic material. In the arrangement shown, the spring member 7 of Fig. 1 is replaced by a substantially rigid arm 12, having a baffle or shelf portion 13 at its upper end, and pivotally mounted in the 35 tower by the lower end as at 14. Movement of the arm 12 is accomplished by means of electromagnets 11 and 11a mounted in opposed relation within the tower, and acting upon armatures 10 and 10a disposed on opposite sides of the 40 pivoted arm 12. Wires 15, 15a, 16 and 16a, connected to the respective electromagnets 11 and 11a, are passed through sealed openings in the tower walls and are suitably protected therein. The action of the apparatus thus described 45 is substantially similar to that of Fig. 1, except that movement of the arm and baffle members is entirely dependent upon electromagnetic means.

In Fig. 3, another form of apparatus, accord- 50 ing to this invention, is shown. The tower 1, in this instance, is provided with a side chamber 17 disposed at substantially the level of the inlet 6. The chamber 17 is not intended to be in free communication with the interior of the 55

tower, but it is not necessarily vapor tight. The electromagnetic means 18, which is disposed in the chamber 17, is preferably of the solenoid type, and has a core member 19 which extends 5 outwardly from the chamber, through an opening 20 in the tower wall, into the upper portion of the tower 1. A baffle member 21 is secured to the outer end of the core member 18 and, under action of the solenoid, may be moved laterally 10 of the tower between the condenser 2 and the inlet 6. An electric current is supplied to the solenoid 18 by means of wires 22 and 23 which pass through sealed openings in a wall of the chamber 17.

15 In operation, a certain desired reflux ratio having been decided upon for the system, the means for activating the electromagnet is suitably adjusted to provide the required intervals of reflux to the column and of product withdrawal therefrom. Distillation and fractionation is then begun. Assuming the use of a conventional timing mechanism to alternately make and break the circuit by which the magnet is energized, the armature will in like manner be 20 drawn toward the column wall by the magnetic force, and moved away by the action of the spring to which the armature is secured. In this fashion, the baffle normally disposed over the inlet of the product recovery line will, in repeated movements, uncover and recover the inlet for such periods of time as have previously been determined as adequate to obtain the desired results.

30 It should be apparent, that the foregoing description of the system and its method of operation is set forth for the purpose of illustration, and that various changes and modifications will be apparent to those versed in the art without departing from the inventive concept as set forth 35 in the appended claims.

I claim:

1. A system for the fractionation of vaporizable liquids comprising in combination with a tower having a vapor space in the upper portion, 45 a means for condensing vapors, returning condensate in a stream to the tower, a conduit, for withdrawing condensate as a product, extending into said tower and opening upward within said vapor space to receive the stream, baffle means 50 for the open end of said conduit, movable with respect thereto from a position intercepting the stream to a position clear of the stream and return, and electromagnetic means for effecting 55 said movement of the baffle.

55 2. A system for the fractionation of vaporizable liquids comprising in combination with a tower, a means for condensing vapors returning condensate to the tower, a conduit extending into the tower for withdrawing said condensate as a 60 product, a baffle disposed within said tower and movable to shield the open end of said conduit, diverting the condensate therefrom as reflux to the tower, and means for moving said baffle by the action of an electromagnetic force away from 65 the conduit to permit the condensate to flow into the conduit.

70 3. A system for the fractionation of vaporizable liquids comprising in combination with a tower, a means for condensing vapors returning condensate to the tower, a conduit extending into the tower for withdrawing said condensate as a product, a movable baffle shielding the open end of 75 said conduit, diverting condensate therefrom as a reflux to the tower, an armature connected to said baffle, and means for moving said baffle

away from the conduit by the action of an electromagnetic force on the armature.

4. A system for the fractionation of vaporizable liquids comprising in combination with a tower, a means for condensing vapors returning condensate to the tower, a conduit extending into said tower for withdrawing condensate as a product, a movable baffle shielding the open end of said conduit, diverting condensate therefrom as a reflux to the tower, electromagnetic means for 10 moving said baffle away from the conduit, and spring means for repositioning the baffle to shield the open end of said conduit.

5. A system for the fractionation of vaporizable liquids comprising in combination with a tower, a means for condensing vapors returning condensate to the tower, a conduit extending into said tower for withdrawing condensate as a product, spring means secured in said tower adjacent the conduit, a shield for the open end of said conduit, to divert condensate therefrom as reflux to the tower, said shield supported by said spring means, an armature on said spring means, and an electromagnet acting upon said armature to move said shield against the resistance of said 25 spring means.

6. A system for the fractionation of vaporizable liquids comprising in combination with a tower, having a vapor space in the upper portion, a means for condensing vapors, returning condensate in a stream to the tower; a conduit for withdrawing the stream of condensate as a product, extending into said tower, and opening upward within said vapor space; baffle means for the open end of said conduit movable with respect thereto laterally of the tower; an arm movably supporting said baffle, pivotally mounted within the tower to move the baffle from a position intercepting the stream to a position clear of the stream; armature members secured 40 to said arm in opposed relation at a point intermediate the ends, and extending laterally toward the tower walls, electromagnets secured to said walls substantially concentric with said armatures; and means for energizing the electromagnets in sequence whereby the above movements of the baffle are effected.

7. A system for the fractionation of vaporizable liquids comprising in combination with a tower, having a vapor space in the upper portion, 50 a means for condensing vapors, returning condensate in a stream to the tower, a conduit for withdrawing the stream of condensate as a product, extending into said tower and opening upward within said vapor space, a side chamber secured to the outer face of one wall of the tower substantially at the level of the open conduit end, a solenoid in said chamber, a core member in said solenoid extending through an opening in the wall of the tower, baffle means carried by said core member, and disposed intermediate the condensing means and the open conduit end, said core member and baffle means being movable with respect to said open conduit end by the action of the solenoid from a position 60 intercepting the stream to a position clear of the stream and return.

75 8. A system according to claim 1 in which the means for moving said baffle by the action of an electromagnetic force consists of an electromagnet disposed within the tower and energized from a source of electric current outside the tower, and an armature connected with said baffle and disposed within the field of said electromagnet.

9. A system according to claim 1 in which the means for moving said baffle by the action of an electromagnetic force, consists of an electromagnet disposed outside the tower, means for energizing said electromagnet, and an armature connected with said baffle and disposed within the field of said electromagnet.

10. A system according to claim 1 in which the means for moving said baffle by the action of an electromagnetic force, consists of a solenoid within the tower, and energized from a source of electric current outside the tower, in which the magnetic core is connected to said baffle.

ANTHONY E. ROBERTSON.
